VARIABLE DELIVERY GEAR PUMP

Howard M. Purcell, Mount Gilead, Ohio, assignor
to H-P-M Development Corporation, Wilming-
ton, Del., a corporation of Delaware

Application June 22, 1945, Serial No. 600,890

3 Claims. (Cl. 103—120)

1

This invention relates to fluid pumps and, particularly to gear pumps.

The usual type gear pump comprises a pair of pumping gears which run together in mesh within a pump casing which has an inlet port and an outlet port. The gears transfer fluid from the inlet port to the outlet port at a substantially constant rate of flow. If the entire discharge from the pump is not used it must be discharged through a bleed off valve or through a relief valve to exhaust. This is wasteful of power and is disadvantageous in that it heats the oil and also in that it permits the pump discharge pressure to vary.

In the usual type gear pump the only means available for varying the rate of discharge thereof is a variable speed drive. Such a drive is inconvenient and expensive and is not well adapted for mounting in a machine base or in other locations where pumps are usually located.

Accordingly, it is a primary object of the present invention to provide a gear pump having means for varying the discharge rate thereof.

It is another object to provide a gear pump having a substantially constant discharge pressure.

It is still another object to provide a gear pump which is driven from a constant speed source of power and which has a variable rate of discharge.

In a simple two gear pump the only way of reversing the direction of discharge is to reverse the direction of rotation of the pumping gears. This involves the use of a reversible motor or of a reversible transmission.

Accordingly, it is still another object of this invention to provide a gear pump which may be reversed.

It is another object to provide a reversible, variable delivery gear pump which is driven from a substantially constant speed source of power.

The objects of this invention are carried out in general by providing one or more gears in a gear pump which are adapted axially to slide thereby to vary the degree of mesh thereof with another or other pumping gears. Means may be provided for positioning the gears in any degree of mesh thereby to adjust the rate of discharge of the pump and other means may be provided whereby the gears may shift into or out of mesh in response to the discharge pressure of the pump thereby providing for a pressure limiting or pressure holding feature.

By providing a pair of sliding gears in mesh with a driven gear, a gear pump may be pro-

2

vided which is reversible as well as being variable delivery.

It is, therefore, still another object to provide a variable delivery gear pump comprising a plurality of pumping gears which are axially slidable relative to one another thereby to vary the rate and direction of delivery from the said pump.

These and other objects and advantages of this invention will become more apparent upon reference to the accompanying specification and drawings in which:

Figure 1 is a vertical section through a variable delivery gear pump having one stationary gear and one slidable gear;

Figure 2 is a transverse section on the line 2—2 of Figure 1;

Figure 3 is a section taken on the line 3—3 of Figure 4;

Figure 4 is a section taken on the line 4—4 of Figure 3 and illustrates one type of three gear variable delivery gear pump;

Figure 5 is a section indicated on the line 5—5 on Figures 3 and 4;

Figure 6 is a section indicated on the line 6—6 of Figure 3;

Figure 7 is a vertical section through a three gear pump constructed somewhat differently than the pumps of Figures 3 to 6 inclusive;

Figure 8 is a section taken on the line 8—8 of Figure 7; and

Figure 9 is a simplified view showing an arrangement employing four pumping gears.

Referring to the drawings, particularly Figures 1 and 2, 10 indicates a pump casing comprising the central block 12 which is apertured for receiving the pumping gears 14 and 16, and to which are secured end plates 18 and 20. The plates 18 and 20 are bored for receiving the bearings 22 which rotatably support the gear 14 and the plate 18 is further bored for receiving the drive shaft 24 through which power is transmitted to the pumping gears. An oil seal 26 fits around the shaft 24 and prevents the leakage of fluid from within the pump casing.

The pumping gear 16 is rotatably supported on a shaft 28 which terminates at its right end in a threaded portion which receives the nut 30. The shaft 28 is integral with a block 32 which fits against the left face of the gear 16. The nut 30 fits within an aperture 34 in the casing portion 20 and is engaged by a spring 36 which thrusts leftwardly against the nut and gear. The thrust of the spring 36 is adjustable by means of a screw and lock nut arrangement at 38 which

passes through the cap 40 secured to the plate 28 of the casing 10.

The block 32, more particularly seen in Figure 2, comprises a key way adapted for engagement with a key 42 carried in the plate 18 of the housing and further comprises an arcuate notch at 44 which is closed by a depending and similarly shaped projection 46 on the plate 18. The notch 44 is shaped exactly to receive the periphery of the gear 14 as the gear 16 is axially shifted thereto. The block also comprises the arcuate notch 33 which is connected by the bore 35 with the pumping zone of the gears whereby the gear 16 and block 32 are partially hydraulically balanced to facilitate their shifting.

The block 32 is abutted by or has integral therewith a piston portion 48 which extends into a bore 50 in the plate 18. A screw 52 which has lock nuts thereon is threaded through the wall of the plate 18 in order adjustably to abut the piston portion 48 thereby to vary the relative position of the gears 14 and 16. The bore 50 is connected by a channel 54 with the outlet port indicated at 56 of the pump. Thus, in response to a predetermined pressure at the discharge port 56, the piston 48 is operable to move the gear 16 transversely of the gear 14 thereby to vary the degree of mesh thereof and thus to vary the pump discharge rate.

The nut 30 is adapted for abutment with the cap 40 at a point which maintains the gears 14 and 16 partially in mesh. This is for the purpose of insuring that the gear 16 will return under the influence of the spring 38 when the opposed thrust thereon is released.

It will be apparent that the capacity of the pump of Figure 1 cannot be reduced to zero because of the minimum amount of mesh of the pumping gears but the said minimum amount of mesh may be adjusted until the quantity of fluid pumped is only sufficient to make up for leakage within the pump and in the device to which the pump is supplying fluid.

Referring to Figures 3 and 6 inclusive, there is illustrated a pump comprising a casing generally indicated at 60 which includes an inlet 62 and an outlet 64 and within which are rotatably mounted three pumping gears numbered 66, 68 and 70. The gear 66 has connected therewith the drive shaft 72 and is mounted in anti-friction bearings suitably supported within the pump casing 60. The gear 68 is carried on or has integral therewith a shaft 74 and is adapted for continuously meshing with the driven gear 66.

The gear 70 is the sliding gear and is rotatably mounted on a shaft 76 which is integral with a block 78. The end of the shaft 76 is threaded for receiving a nut 80 which retains the gear in position against the block 78. The shaft 76 is bored from the end thereof as at 82 for receiving the plunger 84 which is adapted for abutment with a screw 86 extending through the cap 88 and being locked in position by the lock nuts 90.

The block 78, similarly as the block 32 in Figures 1 and 2, is provided with an arcuate notch 92 adapted for receiving the periphery of the gear 66 as the gear 70 is adjusted axially relative thereto. Also, similarly to the block 32, the block 78 is provided with the transverse bore 94 which communicates with the segmental area 96 and with the pressure port of the pump thereby at least partially hydraulically to balance the block 78 so that the shifting of the gear 70 may be more easily accomplished. The bore 94 communicates by means of a bore 98 with the cylinder 82 for the

purpose of shifting the gear 70 in response to pump pressure as will hereinafter be described.

Referring to Figure 5 the means for shifting the gear 70 are more particularly shown. There is provided within the pump casing a pivoted lever 100 which bears at one end against the block 78 and, at its other end, against a spring 102, the thrust of which is adjustable by means of a nut and screw arrangement at 104. The arm 100 is divided in approximately the ratio of 1 to 2 so that the movement of the spring is about one-half the movement of the gear 70. This permits a shorter, stiffer spring to be employed than could be used if the gear 70 directly engaged the said spring.

The operation of the pump will be evident upon reference to Figures 4 and 6. Assuming that the gears are fully meshed and that the gear 66 is being driven in the direction indicated by the arrow in Figure 4, the gear 68 is transferring fluid away from the inlet passage at 106 while the gear 70 is transferring fluid from the pressure discharge passage 108. The gear 66 is transferring fluid from the discharge passage 110 so that the total result of the three gears fully meshed is merely a transfer of fluid within the pump and no transfer of fluid from the inlet port 62 to the discharge port 64.

If, now, the gear 70 is moved partially out of mesh with the gear 66, the gears 66 and 68 deliver at full capacity to the discharge port 110 while the gears 66 and 70 withdraw at partial capacity from the discharge port 108. The result is a discharge from the discharge port 64 at a rate which is the difference of the aforementioned pumping rates. It will be apparent that the discharge rate of the pump is in inverse ratio to the degree of mesh of the gears 66 and 70.

The spring 102 normally urges the gear 70 to a position where it is substantially out of mesh with the gear 66. Hence, as the pressure at the discharge port of the pump builds up, the pressure is conducted through the passages 94 and 98 to the cylinder 82 where it bears against the piston 84 and urges the gear 70 into a position of greater degree of mesh with the gear 66. The pump is thus adapted for pressure holding or pressure limiting. The screw at 86 provides a means whereby the capacity of the pump may be varied independently of its pressure characteristics while the screw at 104 provides means for adjusting the maximum discharge pressure of the pump.

In Figure 7 there is illustrated a modified arrangement employing the three gears 110, 112 and 114 of which the first is the driven gear and the latter two are both slideable. Inasmuch as the mechanism associated with the sliding gears is similar to that shown in Figures 1 to 6, no particular description thereof will be given in connection with Figure 7.

In Figure 8 there is illustrated the condition which prevails when the three gears are fully in mesh. With the gears fully in mesh and rotating in a direction of the arrows, the gears 110 and 112 are displacing fluid from the port 116 to the port 118 while the gears 110 and 114 are displacing an equal amount of fluid in the opposite direction. The total result of this exchange of fluid is to transfer fluid within the pump and not from one of the ports 116, 118 to the other.

If, however, one of the gears 112 or 114 is moved at least partially out of mesh with the gear 110, the result will be to discharge fluid from one of the ports 116 or 118. If the other gear is moved partially out of mesh the opposite result

will obtain so that complete reversal of the flow from the pump may be had by selectively shifting one or the other of the gears 112, 114 out of mesh with the gear 110.

The shifting of the gears 112, 114 may be accomplished by means of the screws 120, 122 which thread through the side wall of the pump casing 124. The gear which remains in mesh with the gear 110 may be provided with a plunger such as those indicated at 126 and 128 in association with the gears 112 and 114 respectively, which is connected with the discharge ports of the pump so that at a predetermined discharge pressure the gear will be shifted out of mesh with the gear 110 thereby providing for a pressure holding or a pressure limiting feature. Optionally, the gear which is out of mesh with the gear 110 may be similarly shifted into mesh under pressure thereby to reduce or to limit the pump discharge. As indicated in Figure 8, the plunger 126 of the gear 112 may be connected by a passage 130 with the discharge port 118 while the plunger 128 of the gear 114 may be connected by the passage 132 with the discharge port 116.

There is illustrated in Figure 9 still another arrangement for obtaining a reversible variable delivery pump, this modification employing four gears rather than three. In Figure 9 the gear 150 and the gear 152 rotates in mesh continuously within the pump casing 154. There is provided also the gear 156 which meshes with the gear 150 and which is mounted on trunnions so as to be axially slidable similarly as the sliding gears in the previous figures. A fourth gear 158 is also trunnion mounted and is axially shiftable in mesh with the gear 152. The pump casing 154 comprises the passageways or ports 160 and 162 which communicate with the pumping zones of the gears.

When the gears are fully in mesh and are being rotated in the direction indicated by the arrows they are transferring fluid from the port 160 to the port 162. When the slidable gears 156 and 158 are half meshed with their associated gears 150 and 152 there is no transfer of fluid between the ports 160 and 162. When the sliding gears are substantially out of mesh, the transfer of fluid is from the port 162 to the port 160.

The gears 156 and 158 may be mechanically moved in either direction so as to select the direction of delivery of the pump and may further be provided with yielding means and fluid pressure responsive means properly connected with the ports 160 and 162 so the pump will hold or limit pressure in either direction of delivery thereof.

While no means for balancing the gears have been shown, it will be understood that any well known arrangement for hydraulically balancing the said gears could be used in order to increase the available discharge pressure and to give better operating efficiency.

It will be understood that various modifications and arrangements in structure could be made without departing from the spirit of my invention and, accordingly, I desire to comprehend such modifications and substitutions of equivalents as may be considered to come within the scope of the appended claims.

I claim:

1. In a gear pump; a casing having an inlet port and an outlet port; a first pumping gear rotatably mounted within said casing; a second pumping gear rotatably mounted within said casing in mesh with said first gear; a third pumping gear in mesh with said first gear and mounted

within said casing for rotation and for relative axial sliding movement with respect to said first gear for varying the degree of mesh thereof with said first gear; a first passageway in said casing

- 5 communicating with the outlet port thereof and disposed adjacent the meshing portions of said first and second gears to receive fluid circulated by said first and second gears; a second passageway in said casing communicating with the outlet
- 10 port thereof and disposed adjacent the meshing portions of said first and third gears to supply fluid for circulation by said first and third gears when the latter is fully meshed with said first gear and to receive fluid circulated by said first
- 15 gear when said third gear occupies a position other than a position of full mesh with respect to said first gear, spring and lever means to urge said third gear to a position of minimum mesh with respect to said first gear; and means responsive to a predetermined pressure at the outlet port of said casing to move said third gear toward a position of full mesh with respect to said first gear.

- 2. In a gear pump having a casing formed with a fluid inlet, a fluid outlet, and an internal gear chamber communicating with the fluid inlet by way of a single passage and with the fluid outlet by way of a pair of separate passages; a first driving gear rotatably mounted within the gear
- 25 chamber of said casing between the two passages communicating with the fluid outlet of the casing; a second pumping gear rotatably mounted within the gear chamber of said casing adjacent one of the passages communicating with the fluid outlet and in mesh with said first driving gear, said second pumping gear being operable upon rotation of said first driving gear to circulate fluid between the fluid inlet and one of the passages communicating with the fluid outlet;
- 30 and a third pumping gear in mesh with said first driving gear and mounted within said casing adjacent the other passage communicating with the fluid outlet thereof for rotational and relative axial sliding movement with respect to said first driving gear whereby to vary the degree of mesh thereof with said first driving gear, said third gear being operable upon rotation of said first gear and when fully meshed therewith to circulate fluid between the last-named passage
- 35 and a fourth pumping gear in mesh with said first driving gear and mounted within said casing adjacent the other passage communicating with the fluid outlet thereof for rotational and relative axial sliding movement with respect to said first driving gear whereby to vary the degree of mesh thereof with said first driving gear, said fourth gear being operable upon rotation of said first gear and when fully meshed therewith to circulate fluid between the last-named passage
- 40 and a fifth pumping gear in mesh with said first driving gear and mounted within said casing adjacent the other passage communicating with the fluid outlet thereof for rotational and relative axial sliding movement with respect to said first driving gear whereby to vary the degree of mesh thereof with said first driving gear, said fifth gear being operable upon rotation of said first gear and when fully meshed therewith to circulate fluid between the last-named passage
- 45 and a sixth pumping gear in mesh with said first driving gear and mounted within said casing adjacent the other passage communicating with the fluid outlet thereof for rotational and relative axial sliding movement with respect to said first driving gear whereby to vary the degree of mesh thereof with said first driving gear, said sixth gear being operable upon rotation of said first gear and when fully meshed therewith to circulate fluid between the last-named passage
- 50 and a seventh pumping gear in mesh with said first driving gear and mounted within said casing adjacent the other passage communicating with the fluid outlet thereof for rotational and relative axial sliding movement with respect to said first driving gear whereby to vary the degree of mesh thereof with said first driving gear, said seventh gear being operable upon rotation of said first gear and when fully meshed therewith to circulate fluid between the last-named passage

- 55 3. In a gear pump; a casing formed with a fluid inlet, a fluid outlet, a pumping chamber, a single passageway connecting the fluid inlet with the pumping chamber at one end thereof, and a pair of relatively spaced separate passageways connecting the fluid outlet with the pumping chamber at its opposite end; a first driven pumping gear rotatably mounted within the pumping chamber of said casing between the pair of passageways communicating with the fluid outlet;
- 60 a second pumping gear rotatably carried within the pumping chamber of said casing in mesh with said first pumping gear and disposed adjacent one of the pair of passageways communicating with the fluid outlet of said casing, said second gear being operable upon rotation of said first gear to circulate fluid from the passageway communicating with the fluid inlet to the passageway adjacent thereto communicating with the fluid outlet of said casing; and a third pumping gear in mesh with said first gear mounted
- 65
- 70
- 75

within said casing for rotational and axial sliding movement with respect to said first gear whereby to vary the degree of mesh thereof with said first gear and disposed adjacent the other of the pair of passageways communicating with the fluid outlet of said casing, said third gear when occupying a position of full mesh with said first gear and when rotated thereby serving to circulate fluid from the passageway adjacent thereto and communicating with the fluid outlet to the passageway communicating with the fluid inlet, and when occupying a position substantially out of mesh with said first gear providing for the circulation of fluid by said first gear from the passageway communicating with the fluid inlet to the passageway adjacent said third gear communicating with the fluid outlet of said casing.
